UNITED STATES PATENT OFFICE

2,604,968

ADAPTER FOR TYPEWRITERS

Louis Jensen, Chicago, Ill., assignor to Uarco
Incorporated, a corporation of Illinois

Application February 16, 1951, Serial No. 211,412

4 Claims. (Cl. 197—126)

1

This invention relates to an adapter or device for enabling continuous-form stationery to be used in a conventional typewriting machine, and more particularly to an adapter having improved means for mounting a carbon carriage which travels to and from the typewriter carriage. The present invention is an improvement on the device shown in my Patent No. 2,109,923, issued February 22, 1938.

The primary object of the invention is to provide an improved stop member and latching lever for holding the carbon carriage while stripping a completed set of forms forwardly, and automatically releasing the carriage for forward movement when the next set of forms, interleaved with the carbon, is again advanced by the typewriter platen.

Another object of the invention is to provide an improved adjustable support for the guide member on which the carbon carriage is anti-frictionally mounted.

The invention is illustrated in a preferred embodiment in the accompanying drawings, in which:

Figure 1 is a fragmentary plan view of a machine embodying the invention; Fig. 2, a fragmentary vertical sectional view, taken as indicated at line 2—2 of Fig. 1; Fig. 3, a bottom plan view of the guide member with its adjustable stop and releasing lever; Fig. 4, a fragmentary side elevational view of the same; Fig. 5, a plan view of the stop member, taken as indicated at line 5—5 of Fig. 4; Fig. 6, a fragmentary vertical sectional view, taken as indicated at line 6—6 of Fig. 4; and Fig. 7, a vertical sectional view, taken as indicated at line 7—7 of Fig. 4.

In the embodiment illustrated, a base plate 8 has at its rear portion upwardly extending arms 9 on which channel members 10 may be telescoped. A typewriter, not shown, may be placed on the base and positioned laterally by slideable positioning members 11 held by screws 12. Stop members 13 held by thumb screws 14 engage the rear of the typewriter to position it longitudinally on the plate.

A plate-like track 15 is secured to the channel members 10 by means of brackets 16. A shiftable carriage 17 is provided, with top rollers 18 to engage the top edge of the plate 15, and bottom rollers 19 to engage the bottom edge of said plate. The carriage is also provided with a forwardly extending bracket 20, provided with a pair of rollers 21 to bear against the front face of the upper portion of the plate 15.

The shiftable carriage 17 has a cross-bar 22

on which are mounted a pair of forwardly extending adjustable arms 23, to engage the ends of the typewriter carriage and cause the shiftable carriage to travel laterally with the typewriter carriage. The carriage 17 also has a pair of upwardly extending fingers 24 which are adjustable laterally in slots 25, to accommodate different widths of continuous-form stationery.

A rearwardly extending guide plate 26 has at its front end a pair of socket members 27 which make a hinged connection with the carriage 17, by means of a fixed pintle 28 and a removable pintle 29 having a thumb screw 30 making threaded engagement with the carriage. The guide member 26 has brackets 31 near its central portion, to which are pivotally connected a pair of supporting links 32 which are provided at their lower ends with a connecting cross-bar 33. The back of the shiftable carriage 17 has a pair of notched uprights 34 to receive the cross-bar 33. The adjustable supporting links 32 support the guide member 26 at a desired inclination, depending upon which pair of notches receive the cross-bar 33.

25 A carbon carriage 35 has grooved anti-friction rollers 36 which engage the lateral edges of the guide member 26 which serves as a track. The carbon carriage is shown in Fig. 1, with a superstructure 37 provided with carbon-holding blades 38. This superstructure has its front edges held by hooks 39 and a spring-held catch 40. The guide member has a longitudinally extending slot 41, through which depends an L-shaped catch 42 from the carbon carriage 35.

35 A latch lever 43 is fulcrumed to the lower central portion of the guide member 26, as indicated at 44. A torsion spring 45 urges the front end of the lever upwardly. An actuating finger or arm 46 is carried by rearwardly extending arms 47, adjustably secured to the front end of the lever by means of brackets and screws 48.

The latch lever 43 has two bars connected at their rear ends at 49 and at their front ends by a bracket 50. The lower edges of the bars are notched, as indicated at 51, and a U-shaped stop member 52 is slidably mounted on said bars, and has a downwardly extending finger piece 53, as best shown in Fig. 4. A generally Z-shaped slotted trigger member 54 has a catch 55 to be engaged by the hook 42, and has a downwardly extending finger 56. The member 54 is movably secured to the slide by a machine screw 57 which extends loosely through the slide member and is provided with a compression spring 58, so as to 50 yieldingly urge the shoulders 59 into engagement

with a selected pair of notches 51. Thus, it will be understood that by squeezing the finger pieces 56 and 53 together, the stop member may be slid along the lever 43 to a desired longitudinal position. Also, when the carbon carriage slides backwardly, the inclined portion of the hook 42 will raise the rear portion of the lever 43 against the action of the spring 45 and snap it into the position shown in Fig. 4. The carbon carriage may be released from the stop member by depressing the actuating finger 46.

The operation of the device is substantially the same as shown in my Patent 2,109,293. Continuous-form stationery strips with interleaved carbon sheets, held by the bars 39, are led from the back of the attachment to the platen roll. As the paper is fed under the platen roll, the finger 46 is depressed and automatically releases the carbon carriage, so that it may travel forwardly with the stationery. After a set of forms has been filled in, the stationery is withdrawn from under the platen and the assembly will move backwardly until the carbon carriage is stopped and held by the stop member. The stationery strips are then drawn forwardly while the carbon sheets are held, stripping them into the next succeeding set of forms. After the completed set of forms is detached, the next set of forms is fed by the platen into writing position and the carbon carrier is again released automatically. The angle of the guide member 26 may be adjusted to a desired angle, depending upon the number and weight of the forms, so that the force of gravity will assist in sliding the carbon carriage back to its latching position. The present construction is much lighter and stronger than the earlier devices and requires no permanent connection with the typewriter.

If it is desired to remove the rearwardly extending guide member, it is merely necessary to loosen the single screw 30 and lift off the back section.

The foregoing detailed description is given for clearness of understanding only, and no unnecessary limitations should be understood therefrom, for some modifications will be obvious to those skilled in the art.

I claim:

1. An attachment for adapting a typewriter to continuous-form stationery comprising: a sta- 50

tionary lateral track; a shiftable carriage mounted on said track and adapted to travel with the carriage of a typewriter, said shiftable carriage having on its rear portion an upwardly extending standard; a rearwardly extending guide member having its front end hinged to the shiftable carriage and provided with a forwardly extending supporting link adapted to adjustably engage said standard to regulate the inclination of said guide member; and a carbon carriage anti-frictionally mounted on the guide member for travel to and from said shiftable carriage.

2. An attachment as specified in claim 1, in which the standard is in the form of a pair of notched uprights, and the supporting link has at its front end a cross-bar adapted to engage selectively pairs of notches in said uprights.

3. An attachment as specified in claim 1, in which the guide member is provided with a forwardly extending latch lever having an actuating finger at its front end, a stop member adjustably mounted on said lever, and a catch on the carbon carriage adapted to engage said stop member and be locked against travel on the guide member until released by depressing said actuating finger.

4. A device as specified in claim 3, in which the latch lever is notched and positioned beneath the central portion of the guide member with the actuating finger extending above said guide member, the stop member is slidably mounted on the lever and has a detent to engage a selected notch in said lever, and the guide member has a longitudinally extending central slot through which the carbon carriage catch extends to engage said stop member.

LOUIS JENSEN.
